ELECTRONIC CIRCUIT

Samuel C. Hurley, Jr., Danville, Ill.; Wilmina L. Hurley, executrix of said Samuel C. Hurley, Jr., deceased, assignor to Wilmina L. Hurley, Danville, Ill.

Application January 4, 1947, Serial No. 720,230

1 Claim. (Cl. 315—207)

1

This invention relates to a means for deionizing a gas-filled tube once it is ionized. It particularly relates to an electronic circuit in which a vacuum tube is connected in parallel with a gas-filled tube across a source of direct current potential.

One of the problems in this art is the deionization of a gas-filled tube which is connected across a source of direct current potential, once it is ionized. In many operations such as photoelectric inspection operations, registration control operations and others, it is necessary to deionize the tube at certain intervals or under certain conditions. It is a characteristic of a gas-filled tube which is connected to a source of direct current potential that once it is ionized, it will continue to ionize until the circuit is broken regardless of how negative in potential the control grid is driven. In the prior art, mechanical switches, time delay relays and other mechanical devices have been used to interrupt the circuit and thereby deionize the gas-filled tube. However such mechanical switches or anything involving mechanical means for interrupting the circuit, have the usual disadvantages that are inherent in mechanical means. Mechanical means are never as instantaneous in their reaction as electronic means. Mechanical means require more upkeep and if a switch sticks, the desired result is not obtained. There is nothing to go wrong with electronic means such as is described herein. Electronic means are instantaneous and will always respond in the required manner.

Broadly my invention comprises a vacuum tube connected in parallel with a gas filled tube across a direct current source of potential. The gas filled tube is controlled by a grid and once it is ionized, it will continue to ionize unless something is done to deionize it. A vacuum tube is connected in parallel with the gas-filled tube and if a sufficient positive bias is placed on the control grid of the vacuum tube, the vacuum tube will draw all the current through the parallel circuit and leave no current to flow through the gas-filled tube and therefore the gas-filled tube will deionize.

While the above arrangement is satisfactory for many purposes, it is not satisfactory where it is desired to insure an immediate stoppage of the flow of current through the gas-filled tube. The immediate stoppage is accomplished by connecting a choke coil in series with the parallel circuit involving the gas-filled tube and vacuum tube across the source of direct current potential. The choke coil has the characteristic of always

2

drawing the same amount of current and by such an arrangement when the vacuum tube draws current below that which would normally be drawn by the choke coil there is no current left to flow through the gas-filled tube and it will deionize.

It is therefore an object of this invention to provide an improved means for deionizing a gas filled tube once it is ionized.

10 Other advantages, objects and uses of my invention will become apparent by referring to the drawing. For sake of illustration the drawing is described in connection with photoelectric means for controlling the grid in the vacuum tube and in the gas-filled tube. However, it is distinctly understood that any means depending upon the kind of operation and the results desired may be employed to control the control grids of the amplifying tubes. The invention 20 resides in the particular means for deionizing the gas-filled tube once the gas-filled tube is ionized.

A gas-filled tube 10 is provided having an anode circuit 11, a cathode circuit 12 and a control grid 13. It is connected to a source of direct 25 current having its positive terminal at 14 and grounded at 15. The control grid 13 in this particular illustration is controlled by a photoelectric circuit employing a phototube 15 connected in series with the resistor 16 across a 30 source of direct current potential having its positive terminal at 17 and its negative terminal at 18. The grid 13 is connected between the phototube 15 and the resistor 16 at the point 19. When the tube 15 is in shadow, a negative 35 potential is placed on the control grid 13 which will prevent the tube 10 from ionizing or conducting a current. When the tube 15 is in light, a positive potential is placed on the control grid 13 and if the circuit otherwise is properly adjusted 40 or controlled, current will flow through the tube 10.

A vacuum tube 20 is also provided having an anode circuit 21, a cathode circuit 22 and a control grid 23. The vacuum tube 20 is connected 45 in parallel with the gas filled tube 10 and the two circuits are joined at the ground 15 and at the point 24. The control grid 23 may be changed from negative to positive depending upon the type of operation by any desired means but for illustrative purposes the following circuit is employed to demonstrate how the device works. A second vacuum tube 25 is provided having an anode circuit 26, a cathode circuit 27 and a control grid 28. The tube 25 is connected to a source 50 of direct current potential having its positive

terminal at 29 and grounded at 30. The vacuum tube 25 is connected in series with the load resistor 31 and the biasing resistor 32. The control grid 23 is connected at the point 33 between the load resistor 31 and the anode 26. The tubes 20 and 25 are so connected that they are 180° out of phase. That is, when tube 25 conducts a current, tube 20 is non-conducting and when the tube 25 is non-conducting, tube 20 is rendered conducting. The control grid 28 is connected to point 34 between the phototube 35 and the resistor 36. The series circuit employing the phototube 35 and resistor 36 is connected to a source of direct current potential having its positive terminal at 37 and its negative terminal at 38.

The operation of the device is as follows: Normally the phototube 35 is in light which places a negative potential on the control grid 28 and a positive potential on the control grid 23. Thus the circuit involving tubes 10 and 20 are normally biased so that the voltage on the control grid 13 controls the flow of current through the tube 10. When the phototube 15 is in darkness, no current will flow through the tube 10. However when the phototube 15 is in light, current will flow through the tube 10 because of the positive potential placed on the control grid 13 from the point 17. However, once the tube 10 is ionized, the control grid 13 no longer can control the flow of current through tube 10 and this is true even though the phototube 15 should be placed in darkness thereby placing a negative potential on the control grid 13. However the tube 10 can be deionized if sufficient positive potential is placed on the control grid 23. If a high positive potential is placed on the control grid 23, the tube 20 will conduct all of the current through the parallel circuit leaving no current left to flow through tube 10 and it would become deionized. This is the condition when the phototube 35 is placed in darkness. When the tube 35 is again placed in light it will place a negative potential on control grid 23 and the circuit employing the tube 10 is again in condition to be controlled by the control grid 13.

In many operations particularly where the circuit can be designed for a particular job, the tube 20 alone upon conducting a current will deionize tube 10. This occurs when the source of potential at 29 is sufficiently high to conduct a large quantity of current through tube 20 which will take all the current from the source 14. However, particularly in circuits where conditions vary, and the exact design cannot be made for all circumstances, it is necessary to employ a choke coil in series with the parallel circuit involving tubes 10 and 20. Choke coil 39 is provided and is connected in series with the adjustable resistor 40 between the point 14 and the point 24. The amount of current which a choke coil will draw depends on the adjustment of the adjustable contact point 41. Thus the adjustable contact point 41 can cause the choke coil to draw a certain amount of current and it can be adjusted so that a given positive pulse received by

the control grid 23 will cause all the current to flow from the point 14 through the choke coil 39, the resistor 40, the tube 20 to the ground 15 leaving no current left to flow through the tube 10 and the tube 10 will become deionized and ready for the next operation or inspection.

My invention resides in having a circuit in parallel with the gas-filled tube, such that said circuit can be caused to conduct all the current 10 and leave no current left for the gas-filled tube 15 to conduct. This is a rapid and accurate way for deionizing a gas-filled tube and a means is provided to insure the deionization of the gas-filled tube at the time it is supposed to deionize 15 for the particular operation being conducted.

Throughout the specification and claims whenever I speak of a positive or negative potential or a positive or negative bias, I mean the relative potential or bias of the control grid in respect with its cathode. The cathode and grid may both be at a positive potential but if the grid is more positive than the cathode, a positive bias or potential is placed on the grid. Likewise both may have a positive potential, but if the grid is less positive than the cathode, a relative negative potential is placed on the grid.

I claim as my invention:

An electronic circuit comprising a source of direct current, a vacuum amplifying tube, a gas-filled amplifying tube, said vacuum tube and said gas-filled tube being connected in parallel with said source of direct current, each of said tubes having an anode circuit, a cathode circuit, and a control grid, a choke coil and a resistor connected in series with said parallel circuit including said vacuum tube and said gas-filled tube, a third amplifying tube having a loaded anode circuit, a cathode circuit and a control grid, the control grid of said vacuum tube being connected to the loaded anode circuit of said third amplifying tube such that the two tubes are 180° out of phase, independent photoelectric voltage-applying means controlling the bias on the control grid of the gas-filled tube thereby controlling the ionization of the gas-filled tube, and means for preventing or stopping the flow of current through the gas-filled tube including voltage-applying means placing sufficient negative bias on the control grid of the third amplifying tube such that the vacuum tube will conduct sufficient current from the direct current source of potential to render the gas-filled tube non-conducting.
